TAPE WINDING BAR LOADER AND UNLOADER

Frank Csutor, Bristol, Pa.

Application May 10, 1956, Serial No. 583,988

9 Claims. (Cl. 242—68)

This invention relates to equipment for winding tape on cores and more particularly to the loading of the cores and spacer sleeves on the winding bars in properly assembled relation and the unloading of the rolls of wound tape and the spacer sleeves from the bars in multiple winding operations in which a wide sheet of material is slit into a larger number of strips and the strips simultaneously wound on a corresponding number of cores.

In such operations a pair of hardwood bars or rods is loaded with an alternating series of cores and spacer sleeves, each having an axial length corresponding to the width of the strips. Then the bars are installed respectively above and below the sheet of tape material in a slitting and winding machine with the cores on one bar coinciding with the spacer sleeves of the other bar and with the cores and spacer sleeves coinciding with the strips as they are formed by cutting instruments in the machine. If an end core on the upper bar, for example, is opposite the first strip cut from the sheet it will be wound on that core and the next strip will be wound on the end core of the lower bar, this alternating arrangement continuing throughout the entire series of cores and bars.

Heretofore in the tape winding operations referred to above it has been the practice to have workers manually load the cores and spacer sleeves on the bars in alternate relation one at a time, and to unload the rolls of wound tape and spacer sleeves from the bar in a disorderly heap, and then sort out the rolls and spacer sleeves, the latter for future use.

One of the principal objects of the present invention is to provide efficient equipment for rapidly loading and unloading the winding bars, each in a single movement and including means for automatically placing a set of cores and spacer sleeves in aligned relation immediately after each bar is loaded, so that in order to load the next bar it is necessary only to insert the bar through concentric openings in the assembled cores and sleeves.

Another object of this invention is to provide a bar loader and unloader of the character mentioned including across its front end a sloping platform on which a large supply of cores may be deposited in irregular relations, across its lower rear end a trough with spaced seats adapted to receive and maintain in axial alignment a series of cores and a series of parallel, rectangular chutes communicating with and of a size to permit free rolling passage of cores from the platform to the trough; and also to provide a second trough across the top of the intermediate portion of the loader and unloader adapted to receive an alternate series of rolls of tape and spacer sleeves on the bar after completion of a tape winding operation, so that the bar can then be unloaded by withdrawing it from the rolls and sleeves; and also including another series of parallel rectangular chutes disposed between the first mentioned series of chutes, also communicating with and of a size to permit free rolling passage of spacer sleeves from the upper to the lower trough

2

into a position between and in axial alignment with cores in the trough through the first mentioned series of chutes, so that a bar may then be loaded by merely inserting it through the aligned cores and sleeves and lifting the whole assembly from the trough.

5 A further object of the present invention is to provide offset and curved entrance ramps leading from the platform into the first mentioned series of chutes, by means of which cores entering the ramp flat on their sides will be guided into an upright or rolling position as they move into the chute entrances; also by means of which the cores are prevented from jamming as would occur in a straight passageway from the platform into the chutes.

Another object of the invention is to provide an adjustable guard to force cores into a flat position before reaching the entrance ramps, and also to stop the movement of cores of a larger size than those being used in current operations.

A still further object of the present invention is to provide a loader and unloader of the character mentioned in which the two series of chutes are formed in plates of uniform thickness and by means of which the entire device can be extended to accommodate as many rolls of simultaneous windings as may be desired.

20 25 Other objects and advantages of my invention will be apparent from the following specification and reference to the accompanying drawings forming a part thereof, in which:

Fig. 1 is a top plan view of one embodiment of my 30 bar loader and unloader;

Fig. 2 is a section taken on the line 2—2 of Fig. 1;

Fig. 3 is a section taken on the line 3—3 of Fig. 1;

Fig. 4 is a front view of the device shown in Figs. 1, 2 and 3, but with the platform and the front plate removed to expose the core chute entrances;

35 Fig. 5 is an elevational view showing a series of rolls and spacer sleeves in position on a bar after completion of a winding operation; and

Fig. 6 is an elevational view showing a series of cores 40 and spacer sleeves on a bar after being lifted from the trough in the lower rear end of the loader and unloader.

In the drawings in which like numerals designate like parts or elements in the several views, it should be understood that, while the loader and unloader is illustrated (in Figs. 1, 3, 4, 5 and 6) with provision for only 45 five cores and four spacer sleeves, to limit the repetitive showing of details, the usual working device would have provision for at least thirty or more cores and a corresponding number of spacer sleeves.

50 The loader and unloader is designated generally by the numeral 10 and comprises a stationary support formed of a plurality of plates 12, which may be made of metal or other suitable material, each adjacent pair of plates having on opposite sides inclined grooves forming 55 a series of parallel, equidistantly spaced chutes 14, rectangular in cross-section and of a size and formation to permit a free passageway for tape winding cores 16 in a rolling condition and an alternating series of parallel, rectangular chutes 18 of a size and formation to permit 60 a free passageway for spacer sleeves 20 in a rolling condition.

The chutes 14 incline toward the front end of the 65 loader and unloader, merging into substantially vertical wells 22 which are partially cut away on one side at the top to form communication with the outlet ends of downwardly inclined ramps 24 which are curved outwardly from the vertical chute portions 22 to terminate in offset entrances 26 communicating with an outwardly inclined platform 28. The lower ends of the chutes 14 terminate in a trough 30 in which semicircular seats 32 corresponding to the diameter of the cores 16 are formed in axial alignment. Alternate semicircular seats 34 are

formed between the seats 32 and in axial alignment therewith to accommodate the spacer sleeves 20, which are usually of a slightly lesser outer diameter than that of the cores 16. The chutes 18 communicate at their lower ends with the seats 34 and at their upper ends with backwardly inclined portions 36 which terminate in semi-circular seats 38 formed in upwardly projecting fingers 40 of a radius to accommodate the outer peripheries of the spacer sleeves 20.

The plates 12 are clamped together with the grooves forming the chutes 14 and 18 in respective facing relation by means of rods 42 and nuts 44, or by other suitable means. Obviously any number of corresponding plates may be thus assembled to accommodate as many cores and spacer sleeves at a time as may be desired.

The vertical wells 22 may be closed in front by a vertically arranged front plate 46 by means of screws or other suitable means; and the platform 28 may be attached to this plate as illustrated. A vertically adjustable guard 48 extends across the platform in parallel relation with the front edge of the loader and unloader to force any upright cores into a flat position, so that they will be in the correct relation with the offset entrances 26 to the chutes 14, and also to stop the movement of any cores of a larger size than those in current use. The ends of the guard are slidably mounted in slots 50 in the rail 52 of the platform and are adjusted by means of screws 54 engaging the bottoms of the slots. The whole assembly of plates 10 forming the stationary support may be mounted in a base 56. The ramps 24 may all be formed integrally in a single plate 58, if desired.

As previously mentioned, the tape winding operation is begun by installing a pair of rods 60, called "bars," in a tape slitting and winding machine (not shown) one above and one below the sheet of tape material, each bar being loaded with a corresponding number of alternately arranged cores 16 and spacer sleeves 20, as shown in Fig. 6. The cores on one bar coincide with the sleeves on the other bar, both being of the same length so that each strip of tape will be wound on a core either above or below the sheet of material. After a winding operation is completed each bar is removed from the winding machine together with the rolls of tape 62 and the spacer sleeves assembled on the bar as shown in Fig. 5. The assembly is then placed in the loader and unloader with the sleeves 20 resting in the seats 38 and the rolls between the fingers 40 as more clearly shown in Figs. 1 and 2. The bar is then withdrawn from the rolls and spacer sleeves, thereby permitting the sleeves to roll by gravity into the seats 34 between a series of cores which will in the meantime have automatically rolled by gravity into the seats 32. The rolls of tape 62 when released from the bar will roll down the declined floor 64 into a receiving depression 66. The bar is then inserted through the cores and sleeves in the seats 32 and 34 and the bar will again be loaded as shown in Fig. 6.

It will be seen from the foregoing description that the action of unloading a bar full of rolls and spacer bars and again loading the bar by inserting it through the automatically assembled cores and sleeves requires an extremely limited amount of time as compared with manual loading and unloading of the bars. A supply of cores is deposited from time to time on the platform 28 which sharply slopes toward the entrances 26. Thus they will keep the chutes 14 filled at all times so that when a series of cores is removed from the seats 32 another series will automatically fall into place. The chutes 18 can also be kept filled with spacer sleeves, if desired, but a convenient arrangement is to use the sets of sleeves as they are unloaded from the bar and fall into their aligned positions.

Obviously various changes may be made in the construction of my improved bar loader and unloader with-

out departing from the spirit and scope of my invention. Accordingly, it should be understood that the embodiment of the invention shown and described is intended to be illustrative only and not limited to such specific construction.

I claim:

1. In combination with pluralities of cylindrical tape winding cores and spacer sleeves therefor, all being of substantially uniform axial length and having axial bores of substantially uniform diameter, and a tape winding bar of a suitable diameter and length for insertion through a series of axially aligned cores and sleeves, a device for loading such cores and spacer sleeves on said bar with said cores and sleeves in alternate relation and subsequently unloading the wound rolls of tape and spacer sleeves from said bar, said device including a stationary support for substantially rectangular construction, said support having a series of axially aligned and alternately arranged seats for cores and spacer sleeves extending along its lower rear end and another series of axially aligned and alternately arranged seats for spacer sleeves and spaces for cores and the rolls of tape wound thereon extending across the top of said support intermediate of its ends and in parallel relation with the series of seats in the rear end of the support, a platform attached to the upper front edge of said support, said platform sloping toward said support and having a sufficient area to receive thereon a number of cores, a series of laterally spaced chutes extending from said platform to the core seats in the lower rear end of said support, and another series of laterally spaced chutes extending from the sleeve seats in the upper surface of the support to the corresponding sleeve seats in the lower rear end of said support, the outlet end of each of said last mentioned chutes being disposed between the outlet ends of a pair of said first mentioned chutes, said chutes all being rectangular in cross-section, also declined rearwardly in the support and of suitable sizes to permit the free rolling passage therethrough of said cores and sleeves.

2. A device for loading cores and spacer sleeves on a tape winding bar and subsequently unloading the wound rolls of tape and spacer sleeves from the bar according to claim 1 in which the stationary support is formed of plates of uniform thickness secured together and in which the chutes for the cores and spacer sleeves are formed by identical facing grooves in laterally opposed pairs of said plates.

3. A device for loading cores and spacer sleeves on a tape winding bar and subsequently unloading the wound rolls of tape and spacer sleeves from the bar according to claim 1 in which the front ends of the core chutes include vertical wells merging at their lower ends into said core chutes and include entrances into said wells, said entrances being formed in a manner to guide cores from a flat position on said platform to a rolling position in said chutes.

4. A device for loading cores and spacer sleeves on a tape winding bar and subsequently unloading the wound rolls of tape and spacer sleeves from the bar according to claim 3 in which the entrances to the vertical well portions of the chutes are laterally offset therefrom and provided with curved, declining ramps for guiding the cores from a flat position on said platform to a vertical position in said well portions.

5. A device for loading cores and spacer sleeves on a tape winding bar and subsequently unloading the wound rolls of tape and spacer sleeves from the bar according to claim 3 in which the tops of the vertical well portions of the core chutes are laterally sloping to provide seats for the declining guide ramps and with sufficient space between the ramps to permit the passage therebetween of a core in a sliding position on the floors of the ramps below such spaces.

6. A device for loading cores and spacer sleeves on a tape winding bar and subsequently unloading the wound

rolls of tape and spacer sleeves from the bar according to claim 1 in which the chutes for spacer sleeves include entrance portions which are declined from the sleeve seats intermediate the ends of the support and merge at their lower ends into rearwardly declined portions of the chutes leading into the sleeve seats in the rear bottom end of the support.

7. A device for loading cores and spacer sleeves on a tape winding bar and subsequently unloading the wound rolls of tape and spacer sleeves from the bar according to claim 6 in which a depression is formed in the top surface of the support, the floor of said depression sloping rearwardly from the spacer sleeve seats and being, also tangential at its front end to the peripheries of the rolls of tape and with its rear end merging into a concave abutment having a radius corresponding to that of the peripheries of said rolls, so that when the bar is withdrawn from a series of rolls and spacer sleeves the rolls of tape will roll to the rear end of the depression and fall over on the floor and the sleeves will roll down their corresponding chutes into the seats provided for them between the cores aligned in their seats at the lower rear end of the support. 20

8. A device for loading cores and spacer sleeves on a tape winding bar and subsequently unloading the wound rolls of tape and spacer sleeves from the bar according to claim 7 and including spaced upright fingers projecting from the floor of the depression and adapted to fit between the rolls of tape to hold them and the sleeves against lateral movement in the support when the bar is being withdrawn therefrom.

9. A device for loading cores and spacer sleeves on a 10 tape winding bar and subsequently unloading the wound rolls of tape and spacer sleeves from the bar according to claim 1 and including a guide bar extending across the platform in parallel relation with the ends of the support, and means cooperative with the platform for vertically adjusting the guide bar to such heights as to limit the passage of cores thereunder to those of a certain axial length and only when in a flat sliding position on the platform.
